CLAIM

The ornamental design for a camera, as shown and described.

DESCRIPTION

FIG. 1 is a front elevational view of a camera showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a perspective view thereof; and,

FIG. 8 is a perspective view thereof, with the camera in an opened position. The broken lines are shown for illustrative purposes only and form no part of the claimed design.
